11 Claims. (Cl. 9—2)

This invention relates to a collapsible, extensible and reversible marine vessel useful for recreational purposes. Although described with particular reference to boats, and especially to sailboats, the invention is not limited thereto but, is equally applicable to other marine vessels such as surf boards, aqua planes, floats and the like.

The principal object of the present invention is to provide a collapsible marine recreational vessel which is simple in construction, light in weight, durable and adapted to be broken down into separate sections for easy transport.

At the same time, it is a further object of the present invention to provide a marine recreational vessel which, though separable into segments, is rigid and strong when assembled.

A further object of the invention is to provide a marine recreational vessel of separable segments of expandable length and capacity.

A still further object of the invention is to provide a recreational marine vessel of separable segments which may be combined in a variety of combinations and which may be reversed end-for-end and top-for-bottom.

Other objects of the invention will become apparent as the description proceeds.

To the accomplishment of the foregoing and related ends, this invention then comprises the features herein-after fully described and particularly pointed out in the claims, the following description setting forth in detail certain illustrative embodiments of the invention, these being indicative, however, of but a few of the various ways in which the principles of the invention may be employed.

The invention is illustrated by the accompanying drawings in which the same numerals refer to corresponding parts and in which:

FIGURE 1 is a perspective view of the collapsible recreational marine vessel according to the present invention shown assembled and used as a sailboat;

FIGURE 2 is an end elevation of the prow of the vessel;

FIGURE 3 is a vertical section longitudinally of the vessel on the line 3—3 of FIGURE 1 and in the direction of the arrows;

FIGURE 4 is a transverse section of the line 4—4 of FIGURE 1 and in the direction of the arrows;

FIGURE 5 is a perspective view of the segment comprising the prow end of the marine vessel;

FIGURE 6 is a similar perspective view of the segment comprising the stern segment of the vessel, being identical in structure with that of FIGURE 5, but viewed from the opposite side;

FIGURE 7 is a top plan view of the vessel according to the present invention expanded in length by the addition of a central section; and

FIGURE 8 is a perspective view of the intermediate segment used to extend the length and capacity of the marine vessel.

Referring now to the drawings, the device of the present invention is shown in FIGURE 1 used as a sailboat indicated generally at 10 and composed of two identical separable slab-like structural hull segments 11. One of the hull segments 11 comprises the prow portion of the boat. The other hull segment 11, which is of identical construction but is turned top-for-bottom, comprises the

2

stern portion of the boat. As shown, each of the segments 11 is generally flat and of substantial thickness having a generally flat surface 12 on one side and a generally contoured surface 13 on the other. The side walls 14 and 15 are preferably perpendicular to the flat surface 12 adjacent the inside abutting end edges 16 of each segment and are preferably tapered slightly from the flat surface 12 toward the contoured surface 13 adjacent the tapered or arcuate outer nose end 17 of each segment. Thus, at the prow of the vessel the side walls taper downwardly to streamline the vessel and facilitate its movement through the water.

To further facilitate easy movement of the vessel through the water the contoured surface 13 of each of the segments may be tapered slightly from the inside end edge 16 toward the outer nose end 17. At the same time, the contoured surface is desirably shaped to provide a catamaran type bow or prow. Thus, a pair of tapered channels 18 of decreasing width and depth from the outer nose end 17 of each hull segment toward the inner joining end is formed in the contoured surface of each segment. It will be readily understood that the contoured surface 13 of the hull segment 11 comprising the prow of the vessel is adapted to rest in the water, whereas the contoured surface of the corresponding segment comprising the stern of the vessel will be uppermost and the flat surface 12 of that hull segment will be in the water.

The hull segments 11 comprising the vessel are connected together by means of a rigid substantially watertight combination half lap butt and double mortise joint, whose structure is best understood from FIGURES 5 and 6. Each of the hull segments 11 is undercut along a plane midway between the surfaces 12 and 13 to provide a plane lap surface 19. The undercut lap surface 19 extends a distance from the joining end 16 of the segment toward the opposite end of the hull segment a distance at least equal to the thickness of the segment, and desirably twice this distance, and terminates in a transverse abutment wall 21. The faces of the inside end joining edge 16 of the hull segments and the abutment wall surfaces 21 are both shown to be perpendicular to the flat surface 12. It is sufficient, however, that they lie in parallel spaced apart planes. It will be seen that a half lap butt joint is made between the two hull segments by bringing the lap surfaces 19 together and causing the end edge surfaces 16 to abut against the cut back abutment surfaces 21.

In order to impart rigidity to the half lap butt joint between the hull segments a double mortise joint is superimposed. At least one mortise channel or groove 22 is provided in the end joining edge 16 of each of the vessel hull segments. A corresponding and complementary projecting tenon or tongue 23 is provided projecting outwardly from each of the set back abutment walls 21 of each of the hull segments. It will be readily seen that the tenon 23 of one vessel hull segment engages and mates with the mortise 22 of the other vessel hull segment to form a rigid locking joint with the half lap butt joint which is made when the lap surfaces 19 are placed in abutting relationship. Although the mortises and tenons are shown to be rectangular, it will be apparent that this is a matter of preference and choice. They may be of any geometric shape so long as the mortises and tenons engage and mate with one another.

The tongues 23 and channel 22 are mating members. They have the same cross-sectional areas so that the tongue 23 of one segment will mate with groove 22 of the other segment as the two segments are brought together. The longitudinal edge of tongue 23 should just meet the adjacent longitudinal edge formed by the lap surface 19 and the vertical surface of the groove. They should not be joined and they should be separable very slightly, but

there is preferably no perceptible gap or slit. The natural resiliency of the material of which the segments are made then provides the necessary separation to permit the mating parts to be assembled.

In order to impart still further rigidity to the joint between the vessel hull segments, fastening means to secure the segments together are preferably provided. These fastening means also function to prevent accidental separation of the hull segments. One exemplary form of fastening means, which is shown in FIGURE 4, is simply a pair of elongated bolt members 27. A bolt receiving hole 28 extends through each of the segments between the flat surface 12 and the underlying abutting lap surface 19. In order that the bolt holes 28 of both hull segments will be in alignment when the segments are joined together the bolt holes must be equidistant between the end joining edge 16 and the abutment wall 21.

A recess 29 is desirably provided in the flat surface 12 of each of the vessel hull segments around hole 28 for the purpose of receiving the head and nut of each of bolts 27 so that they will not project beyond the surface of the assembled vessel and possibly cause injury to the persons using it. For ease in assembly and disassembly of the vessel, wing nuts or the like are desirably used to secure the bolts in place. In order to avoid excessive weight, bolts formed from aluminum or magnesium are desirably used. In some instances, it may be desirable to reinforce the bolt holes, as for example by insertion of a metallic or rigid plastic tube. Other conventional fastening means which will be readily apparent to those skilled in the art may likewise be used. Among these may be mentioned complementary hooks and eyes in the sidewall portions of each hull segment, attracting magnets in the abutting faces of end edges 16 and abutment wall 21, turnbuckles and pins, and the like.

When the marine vessel of the present invention is used as a boat each of the segments is provided with a centerboard slot 24 extending through the flat surface 12 of each vessel segment and a corresponding centerboard slot 25 extending through the tenon 23. The centerboard slots are in registry with one another and are aligned with the longitudinal center lines of the hull segments. A centerboard 26 extends through the slots 24 and 25 to function as a stabilizer or keel for the assembled vessel. The centerboard may be inserted into the slots from either side of the assembled vessel, contributing to the reversability of the device.

A mast socket 31 is provided in the flat surface 12 of each of the vessel segments. The mast socket 31 is aligned with the centerboard slot and desirably extends most of the distance through the segment in order to rigidly support the mast, but be closed on the bottom to prevent the passage of water through the socket. Since each vessel hull segment contains a mast socket 31, only one of these sockets is in use to support a mast at any given time. Passage of water through the unused mast socket is desirably prevented for the comfort of the users of the vessel.

Mast 32 may desirably be formed from aluminum tubing or the like in order to minimize weight. It is also desirably formed from telescoping segments so that it may be reduced to a convenient size for easy carrying. The mast is fitted with a boom 33 and sail 34 in the usual manner.

When used as a boat, the vessel is also provided with a rudder 36 fitted with a tiller or handle 37. The rudder is attached to the stern end of the vessel, for example, by means of a bifurcated clevis-like bracket or fitting 38 attached to the center of the nose end 17 of each of the vessel segments and a corresponding complementary bifurcated clevis-like bracket or fitting 39 attached to the forward edge of the rudder. The rudder is secured in its fittings by means of a pin or bolt 40. The fitting 38 at the prow end of the vessel which is not in use to secure the rudder may be used to fasten a tow line or a mooring line or the like. However, when the vessel is reversed by being

turned over, that fitting then functions to attach the rudder.

As seen in FIGURE 7, the marine vessel according to the present invention may be extended in length and capacity by the insertion of an extension segment 42, whose structure is shown in detail in FIGURE 8. The hull extension segment 42 is of the same width as the joining ends of vessel hull segments 11, and is desirably of approximately the same overall length as those segments. It is of the same overall thickness as the hull segments 11 and has identical generally flat top and bottom surfaces 43 and identical side walls 44 which are desirably perpendicular to the top and bottom surfaces.

The hull extension segment 42 is adapted to be fit in a rigid water-tight half lap butt and double mortise joint to each of the vessel hull end segments 11. In order to accomplish this joint each end of the hull extension segment is provided with an identical lap surface 19A, mortise 22A, tenon 23A, abutting end joining edge 16A and abutment surface 21A, all corresponding to the elements of the same number of the vessel hull segments 11. Thus, when the vessel is extended by means of the hull extension segment 42, the lap surfaces 19 and 19A abut, tenon 23 engages and mates with mortise 22A, tenon 23A engages and mates with mortise 22, end edge 16 abuts against abutment surface 21A and end edge 16A abuts against abutment surface 21. This identical meeting occurs at both ends of the hull extension segment with a pair of vessel segments 11 to form a vessel of extended length. When that extended vessel is to be used as a boat, a central centerboard slot 45 is provided.

When the hull extension segment 42 is used, the centerboard slots in the end segments 11 are closed off in the water tight joint to prevent passage of water through these unused slots. This is accomplished by virtue of the tenons 22A being unslotted and that portion of the top surface 43 of the extension segment being unslotted in the area of mortise 22A. Thus, when the hull extension segment meets with the end vessel segments 11 the slots 24 and 25 in the hull end segments are closed against the passage of water.

Where additional length is desired, additional extension segments may be added in the same manner. The extension segments are reversible so that the extended vessel may be reversed end-for-end and top-for-bottom.

Desirably, the segments comprising the hull of the marine vessel are two-toned as indicated in the drawing, the line of separation between the colors lying on the sidewalls midway between the opposite surface of the hull segments. With such two-toned end segments and extension segments a variety of color combinations can be achieved.

Although the several segments may be made in any desired size, they are desirably in the proportion of about five units by eight units by one unit. Because of the overlap in the area of the connecting joint, two such eight unit end segments may be combined to produce a vessel having a total length of 14 units, and when an extension segment of eight units in length is added, the extended vessel then has a length of 20 units. An exemplary small sailing vessel of convenient size for easy carrying and a capacity of one to three persons may be composed of hull segments which are about 2½ by 4 feet by 6 inches. Two such end segments make a boat which is 7 feet in length. The addition of one extension segment of the same size results in a boat which is 10 feet long.

The vessel segments must be strong, rigid, lightweight and buoyant. They are desirably of solid one-piece construction formed from a rigid synthetic resinous foam material, such as polystyrene or polyurethane or the like. The segments may be formed by working slabs of the rigid plastic foam material to shape, but desirably the plastic foam is formed in situ in a cavity mold so as to produce a structure having an integral smooth outer skin. The vessel segments may likewise be formed from lightweight rigid

sheet material such as aluminum, glass fiber reinforced polyester, marine plywood or the like to produce watertight hollow shells. Alternatively, segments formed from sheet material need not initially be water-tight but may be filled with a plastic foam material formed in situ in the sheet material shell form.

As a convenience in carrying, the sidewalls of the segments may be provided with strap receiving fittings so that the segments may be fastened together by suitable straps, with or without handles, and easily carried. The disassembled vessel may thus be easily carried in a station wagon or on a luggage rack or shipped by public transportation or the like.

Although the invention has been described with particular reference to a flat slab-like vessel which is collapsible, extensible and reversible top-for-bottom, the principle of this invention may also be incorporated into other types of marine vessels having a concave or dished cross-sectional profiles, such as canoes, for example. Such a vessel may be made with two identical hull end sections adapted to be joined together by means of a combination half lap butt and double mortise joint. In this instance, the half lap butt joint of necessity follows the dished contour of the vessel. A plurality of mortise and tenon elements are disposed about the end edge of this contoured surface. Such a vessel is reversible end-for-end and is also adapted to be extended by the insertion of one or more intermediate sections. The hull segments may be of integral one piece construction such as that obtained by plastic foam molding. The hull segments may also be constructed in the conventional manner, from aluminum or fiber glass reinforced polyester resins or the like in the case of canoes, with simply the joint portions constructed according to the present invention. In order to insure water tightness the joint is desirably gasketed.

While the abutting faces of the half lap portions of the combination joint are desirably flat plane surfaces this is a matter of convenience and preference only. Other geometric configurations may be employed so long as the abutting surfaces mate with one another.

It is apparent that many modifications and variations of this invention as hereinbefore set forth may be made without departing from the spirit and scope thereof. The specific embodiments described are given by way of example only and the invention is limited only by the terms of the appended claims.

We claim:

1. A collapsible marine recreational vessel comprised of a pair of identical hull end segments adapted to be rigidly connected in a combined half lap butt and double mortise joint, each of said hull segments being rigid and slab-like and including one generally arcuate nose end and one flat joining end; said joining ends of said hull segments each including an abutting end edge, a lap surface and an abutment wall surface, the end edge, lap surface and wall surface of one of said segments being adapted to abut the wall surface, lap surface and end edge, respectively, of another of said segments; and said joining ends of said hull segments also each including at least one mortise element and at least one tenon element, the tenon element of one of said segments being adapted to engage and mate with the mortise element of another of said segments.

2. A vessel according to claim 1 further characterized in that said hull segments each include one generally flat surface and one generally contoured surface.

3. A vessel according to claim 2 further characterized in that said contoured surface is generally tapered toward the nose end of said hull segment and includes at least one tapered channel terminating at said nose end and tapering in decreasing width and decreasing depth away from said nose end of the hull segment.

4. A vessel according to claim 1 further characterized by the provision of a centerboard slot adjacent the joining end of each of said hull end segments whereby the slot

of one of said segments is in alignment with the slot of the other of said segments when said segments are connected.

5. A vessel according to claim 1 further characterized in that said hull end segments are separated by at least one hull extension segment adapted to be rigidly connected in a combined half lap butt and double mortise joint to said end segments, said extension segment being rigid and slab-like, of substantially the same width and thickness as the joining ends of said hull end segments, and including two oppositely disposed joining ends; each of said extension segment joining ends being identical and including an abutting end edge, a lap surface and an abutment wall surface adapted to abut the wall surface, lap surface and end edge, respectively, of another hull segment; and each of said extension segment joining ends also including at least one mortise element and at least one tenon element adapted to engage and mate with the tenon element and mortise element, respectively, of another hull segment.

10 6. A vessel according to claim 1 further characterized in that said lap surfaces, mortises and tenons extend a distance from the ends of said hull segments equal to about one to two times the thickness of said segments.

7. A vessel according to claim 1 further characterized 15 in that said hull segments are of solid one-piece construction formed from a buoyant rigid synthetic resinous foam material.

20 8. A vessel according to claim 7 further characterized in that said hull segments are formed from rigid resinous foam selected from the class consisting of polystyrene and polyurethane molded to shape and having an integral smooth outer skin.

25 9. A collapsible marine recreational vessel comprised of a pair of identical hull end segments rigidly connected in a combined half lap butt and double mortise joint, each of said hull segments being rigid and slab-like including one generally arcuate nose end and one flat joining end and one generally flat surface and one generally contoured catamaran surface tapered toward the nose and having 30 at least one tapered channel terminating at the nose end of said hull segment and tapering in decreasing width and decreasing depth from said nose; said joining ends of said hull segments each including an abutting end edge, a lap surface and an abutment wall surface in abutting engagement with the wall surface, lap surface and end edge, respectively, of another hull segment; and said joining ends of said hull segments also each including at least one mortise and at least one tenon in mating engagement with the tenon and mortise, respectively, of another hull 35 segment; said lap surfaces, mortises and tenons extending a distance from the ends of said hull segments equal to about one to two times the thickness of said segments.

40 10. A vessel according to claim 9 further characterized in that said hull end segments are separated by at least one hull extension segment rigidly connected in a combined half lap butt and double mortise joint to said end segments, said extension segment being rigid and slab-like, of substantially the same width and thickness as the joining ends of said hull end segments, and including two oppositely disposed joining ends; each of said extension segment joining ends being identical and including an abutting end edge, a lap surface and an abutment wall surface in abutting engagement with the wall surface, lap surface and end edge, respectively, of another hull segment; and each of said extension segment joining ends also including at least one mortise and at least one tenon in mating engagement with the tenon and mortise, respectively, of another hull segment.

45 11. A collapsible marine recreational vessel comprised of a pair of hull end segments adapted to be rigidly connected in a combined half-lap butt and double mortise joint, each of said hull segments being rigid and including one generally arcuate nose end and one joining end; said joining ends of said hull segments each including an abutting end edge, a lap surface and an abutment wall surface,

the end edge, lap surface and wall surface of one of said segments being adapted to abut the wall surface, lap surface and end edge, respectively, of another of said segments; and said joining ends of said hull segment also each including at least one mortise element and at least one tenon element, the tenon element of one of said segments being adapted to engage and mate with the mortise element of another of said segments.
